UNITED STATES PATENT OFFICE

MARY J. WILLARD, OF DECATUR, ILLINOIS

DUST MOP CLEANER

Application filed August 28, 1931. Serial No. 560,034.

The present invention relates to improvements in means for cleaning dust mops or dry mops which will be free from objections that have been incident to the means commonly employed for freeing such articles from contained dust and dirt particles.

The invention provides a very simple, inexpensive, and durable means for effectively cleaning the heads of dry mops in a sanitary manner, the particles dislodged from the mop head being retained in a suitable receptacle.

With the foregoing and other objects in view, the invention consists in a construction and arrangement of parts that will be hereinafter more particularly described in connection with the accompanying drawings, in which

Figure 1 is a vertical sectional view through an embodiment of the invention;

Figure 2 is a top plan view; and

Figure 3 is a horizontal section taken substantially on the line 3—3 of Figure 1.

Referring to the drawings, in the several views of which like parts are designated by the same reference character, the invention is particularly designed for cleaning dust mops or dry mops which commonly comprise a handle 1 and a head 2 formed of fibrous or filamentary material.

After such an article has been used for a relatively short time, the spaces between the strands of the head 2 become filled with particles of dust and dirt and to provide a means for easily and effectively removing such particles is the principal object of the present invention.

The cleaning means of the invention comprises a suitable receptacle 4 having imperforate side walls and a bottom. The top of the receptacle is closed by a cover consisting of two sections 5, 6, which are hinged as at 7 and may be held in closed relation by a suitable catch or latch means 8. At its center, the cover is provided with a suitable opening or passage through which the handle 1 of the mop may extend when it is desired to use the receptacle either as a means for storing the mop or for cleaning the head thereof.

As shown, the section 6 of the cover is provided with a plurality of peripheral slots through which are adapted to extend locking means, each comprising a bolt 9 which is pivotally mounted on the body 4 of the receptacle so that it can be turned upward through the peripheral slot in the cover section, a lock nut 10 engaging the threaded section of the bolt to secure the cover rigidly to the receptacle.

Within the casing or receptacle 4 is removably arranged a basket-like frame which, as shown, comprises three vertically spaced annular rings 11, 12, and 13 that are suitably connected as by vertical rods or tie members 15 so that the frame may be removed or inserted in the receptacle, as a unit, when the cover 5, 6 is removed.

The basket-like frame may be formed of suitable metal rods soldered or otherwise connected to provide a substantially rigid structure and which serves as a support for means adapted to cooperate with the head 2 of a mop and dislodge contained particles of dust or dirt retained therein when the mop is turned about the axis of its handle 1, as will be hereinafter described.

As shown, the basket-like frame is supported within the receptacle by suitable brackets or ears 20 attached to the side walls of the receptacle and a central foot or downwardly extending projection 21 which provides a suitable space between the bottom and side of the frame and the adjacent walls of the receptacle.

A brush 22 having its bristles directed upwardly is arranged to extend diametrically across the bottom of the basket-like frame, said brush being supported in a suitable holder 23 which is connected at its ends to the bottom ring member 13 of the frame. As shown, the side walls of the holder 23 are preferably bent inward slightly over the head or body member of the brush 22 so that the latter is held from relative vertical movement in the supporting frame, but may be readily disconnected from the holder by endwise movement when the supporting frame has been withdrawn from the receptacle 4.

Two vertically extending brushes 24, 25 are arranged diametrically opposite each other at opposite sides of the bottom brush 22 with the bristles thereof directed inward.

- 5 The holders or guides for the vertical brushes 24, 25 are closed at their lower ends and in cross section, such holders are similar to that of the bottom brush 22. However, such vertical brushes may be easily 10 bodily withdrawn from the supporting frame when the cover 5, 6 has been removed or the entire cleaning frame withdrawn from the receptacle 4.

In addition to the cleaning brushes referred to, the inner ends of the bristles of which are so arranged as to contact with the bottom face and sides of the mop head 2 when the latter is properly positioned within the cleaner, the basket-like frame includes a series of bottom and vertical members which provide a series of spaced surfaces with which the filaments of the head 2 of the mop are adapted to contact so that 20 particles of dust or dirt contained between such filaments will be dislodged. As shown, the bottom of the basket-like cleaner frame comprises a series of crimped rods 30, which extend diametrically across the bottom ring 13 and are formed of suitably crimped or 25 corrugated rods, the upper ends of the corrugations extending substantially to the horizontal plane of the free ends of the bristles of the brush 22. Similarly crimped rods 31 connect the bottom and top rings 11, 13 of 30 the removable frame and the inwardly directed portions of such rods form contact surfaces against which the head 2 of the mop will strike as it is oscillated about the longitudinal axis of its handle 1.

35 The rods 30, 31 may be connected with the ring members of the frame by solder or in any other suitable manner so that the entire cleaning device comprising the basket-like frame, the brushes, and the cleaning members 30, 31 may be bodily removed as a unit from the receptacle 4.

If desired, the cleaning means hereinbefore described may be effectively employed for cleaning a mop the handle of which extends through the opening in the cover 5, 6 by merely grasping such handle and oscillating the mop. Preferably, however, mechanical means are provided for effecting such oscillation.

55 As shown, a pinion 40 is detachably clamped to the stem or handle 1 of the mop in such relation to the head 2 thereof that when the latter is in position to be cleaned by the brush 22, such pinion will be in the 60 plane of a gear or rack 41 mounted to oscillate about a suitable pivot stud on the cover section 6 and provided with a suitable actuating handle 42. The hub of the pinion 40, as shown, is recessed or grooved to receive the adjacent edges of the cover sections

5, 6 and act as a vertical support for the mop without interfering with the desired free oscillation thereof.

The mop handle 1 is shown as provided above and below the pinion 40 with resilient 70 guard discs or washers 45, 46, so that when the mop is withdrawn from the cleaner and is being used, there will be no danger of the surface being cleaned being marred by contact therewith of the pinion. As shown, 75 the discs 45, 46 extend radially beyond the periphery of the pinion 40 and also beyond the periphery of clamps 50 by which the pinion is connected with the handle 1.

It is believed that the manner of using 80 and advantages of the invention will be readily appreciated from the foregoing description in connection with the drawings. When it is desired to clean the mop head 2, the section 5 of the cover will be moved outward and the mop handle 1 positioned as shown in Figure 1 of the drawings, in which the pinion 40 is in alignment and engagement with the actuating gear or rack 41. The cover section 5 being closed and secured 90 in position by the catch 8, the mop will be vertically supported and by movement of the handle 42, will be bodily oscillated about the axis of its handle. During such oscillation, the contact of the cleaning 95 brushes 22, 24 and 25, as well as the beater-like action exerted by the rods 30, 31 will effectively loosen and dislodge any particles of dirt and dust that have collected in the head 2 and the same will fall into the 100 space beneath the cleaning means.

It will be noted that the bends or crimps in the vertically extending cleaning members 31 are arranged at different elevations, that is they are not in horizontal alignment, 105 circumferentially of the receptacle. This arrangement provides abutments against which the mop head will strike, when oscillated, over a maximum of vertical surface.

There can, of course, be considerable variation and modification of some of the details shown without departing from the spirit of the invention, and except as where specifically noted in the appended claims, 115 the invention is not to be understood to be limited to the exact details illustrated.

I claim:

1. A cleaner for dust mops comprising a substantially cylindrical receptacle, a removable cover for said receptacle provided with an opening through which the handle of a mop to be cleaned may extend, and cleaning means within the receptacle including a brush and relatively rigid beater members 120 against which the head of the mop is adapted to contact as the mop is bodily turned about the axis of its handle, said brush and beater members being positioned inwardly of the cylindrical side wall of said 125 receptacle.

receptacle and being spaced circumferentially therearound.

2. A cleaner for dust mops comprising a receptacle, a removable cover for said receptacle provided with an opening through which the handle of a mop to be cleaned may extend, and cleaning means within the receptacle including a substantially horizontal brush spaced from the top of the receptacle and having its bristles directed upward, and a plurality of vertical relatively rigid, beater members positioned inwardly of the sides of the receptacle and extending above the horizontal plane of the brush, for the purpose described.

3. A cleaner for dust mops comprising a receptacle, a removable cover for said receptacle provided with an opening through which the handle of a mop to be cleaned may extend, and cleaning means within the receptacle including a substantially horizontal brush, with its bristles directed upward, two diametrically opposite vertical brushes arranged on opposite sides of and spaced from said horizontal brush with their bristles directed inward, and a plurality of vertical relatively rigid, beater members extending above the horizontal plane of the brush, for the purpose described.

30 4. A cleaner for dust mops comprising a receptacle, a removable cover for said receptacle provided with an opening through which the handle of a mop to be cleaned may extend, and cleaning means within the receptacle comprising a substantially cylindrical basket-like frame removably supported within the receptacle, the bottom and side walls of said frame both including a plurality of transversely crimped rods providing a series of projections extending inwardly of the frame, a brush extending radially of the bottom of said frame with its bristles directed upward, and a second brush extending vertically along the side wall of the frame and having its bristles directed inward.

5. A cleaner for dust mops comprising a receptacle, a removable cover for said receptacle provided with an opening through which the handle of a mop to be cleaned may extend, and cleaning means within the receptacle comprising a substantially cylindrical basket-like frame removably supported within the receptacle, a brush holder of channel form in vertical cross section extending diametrically across the bottom of said frame, a brush having its body fitted within and movable lengthwise of the channel of said holder with its bristles directed upward, and a series of beater surfaces disposed adjacent the cylindrical side wall of said frame and extending upward from the bottom thereof at opposite sides of said brush holder.

65 6. A cleaner for dust mops comprising

a receptacle, a removable cover for said receptacle provided with an opening through which the handle of a mop to be cleaned may extend, and cleaning means within the receptacle comprising a basket-like frame removably supported within the receptacle and including annular top and bottom rings, a brush holder extending diametrically across the bottom ring, a brush carried by a said holder and having the free ends of its bristles directed upward, a plurality of crimped rods extending diametrically of the bottom ring, the inner ends of the crimps in said rods being substantially in the same horizontal plane as the inner ends of the bristles of the brush, and a plurality of crimped rods connecting the top and bottom rings, for the purpose described.

7. A dust mop cleaner for use with a mop handle having a pinion thereon, said cleaner comprising a receptacle, a cover for the receptacle having a passage through which the handle of the mop extends, a toothed actuating member pivotally mounted on the cover and adapted to mesh with the pinion on the mop handle, and means within the receptacle for contacting with the lower face and sides of the mop head within the receptacle as the mop is oscillated by operation of said actuating member.

In testimony whereof I affix my signature.

MARY J. WILLARD.
